Fig. 9

FIG. 1 is a perspective view of a combined contact printer and paper safe showing my new design and illustrated in an open position;

FIG. 2 is a perspective view thereof similar to FIG. 1, with the paper safe and contact printer portions in a partially opened condition;

FIG. 3 is a top plan view thereof in fully open position;

FIG. 4 is an end elevational view thereof in the position of FIG. 3;

FIG. 5 is a right side elevational view thereof in the position of FIG. 3;

FIG. 6 is a left side elevational view thereof in the position of FIG. 3;

FIG. 7 is an end elevational view thereof in a closed position;

FIG. 8 is a right side elevational view thereof in the closed position of FIG. 7; and

FIG. 9 is a left side elevational view thereof in the closed position of FIG. 7.

I claim:

The ornamental design of a combined contact printer and paper safe, substantially as shown.
